UNITED STATES PATENT OFFICE.

HENRY G. WERNIMONT, OF WASHINGTON, DISTRICT OF COLUMBIA, ASSIGNEE, BY
MESNE ASSIGNMENTS, TO WILLIAM RAUEN, OF CHICAGO, ILLINOIS.

CAN-OPENER.

1,137,175.

Specification of Letters Patent.

Patented Apr. 27, 1915.

Application filed May 6, 1913, Serial No. 765,797. Renewed September 16, 1914. Serial No. 862,104.

To all whom it may concern:

Be it known that I, HENRY G. WERNIMONT, a citizen of the United States, residing at Washington, District of Columbia, have invented certain new and useful Improvements in Can-Openers; and I do hereby declare the following to be a full, clear, and exact description of the invention, such as will enable others skilled in the art to which it appertains to make and use the same.

My invention relates to certain new and useful improvements in an appliance for opening cans, and it consists of certain novel features of construction and combination of parts as will be hereinafter fully set forth and claimed.

The prime object of my invention, among others, is to provide a reliably efficient tool of the character specified which may be cheaply and expeditiously manufactured, as by forming the same out of a single piece of suitable metal, whereby the handle and cutting blade or blades may be fashioned in order that a maximum amount of utility may be afforded and a minimum amount of cost incurred.

Other objects and advantages will be hereinafter clearly set forth in the following specification, to be considered in connection with the accompanying drawings, of which,

Figure 1 shows a side elevation of my invention complete. Fig. 2 shows an edge view of the cutting blades and the handle. Fig. 3 shows the blank from which Figs. 1 and 2 may be readily formed. Figs. 4, 5 and 6 show a modified form of construction from that presented in Figs. 1, 2 and 3.

In order to conveniently refer to the various features of my invention, numerals will be employed, the same numeral applying to a corresponding part in the several views.

In materializing my preferred form of construction, attention is called to Figs. 1, 2 and 3, wherein it will be observed that I have formed from a single piece of material, the blank of which is shown in Fig. 3, a two bladed cutting appliance, each blade being provided with two cutting edges and the complete tool shown in Figs. 1 and 2 may be readily fashioned by bending the blank illustrated in Fig. 3, along the median line thereof, said line being indicated by the numeral 1, thereby bringing the handle members 2 and 3 in close contact and par-

allel with each other, as shown in Fig. 2, it being understood that said handle members are preferably rounded at their ends as indicated by the numeral 4, thus affording a desirable seating for the hand. Upon the opposite ends of the members 2 and 3, I form cutting blades 5 and 6, which before bending the handles, are bent sharply at right angles to the body portion as indicated by the dotted line 7, to provide the offset 65 or shoulder 8, when said blades are again bent as indicated by the dotted line 9, thereby completing said shoulder 8 and again disposing the blades parallel with each other and with the handle members 2 and 3, so 70 that when the handle members are bent along the median line 1, the said shoulders will extend diametrically opposite from each other, and consequently leave the blades 5 and 6 spaced apart so that one of the blades 75 may be thrust into the top of the can near one edge thereof, thereby disposing the shoulders in position to ride upon the edge of the can incident to the operation thereof.

In Figs. 4 and 5, I have shown the cutting 80 blades 5 and 6 as being separated from each other by the obliquely disposed shoulders 10, and as each of the blades is provided with an integral extension 11, said extensions may be bent closely in contact with the inner 85 sides of the blades, thereby insuring that said blades will be reliably held in spaced relationship to each other. If preferred, however, only one edge of the blank may have the extension 11, and where only one extension 90 is employed, it should be of double length so that it can be folded back on itself, thereby providing the requisite space between the cutting blades.

It will therefore be observed from the 95 foregoing description that I have provided several varied forms of construction, which while different in detail, are productive of substantially the same results, i. e.; a most efficient cutting means for quickly severing 100 the lid of a can or any portion thereof.

It will be observed that great leverage is afforded by the arrangement of the shoulder connecting the blade with the handle, and that no other means will be found necessary 105 to dispose the blade in its operative position and at the same time reliably hold it to its work.

If desired, the aperture 18 may be formed in the ends of the handle section, whereby 110

the tool may be readily suspended when not in use.

In Fig. 6, I wish to call attention to the struck-up tongue sections 19 which correspond to the extensions 11 in Fig. 4, and are designed to subserve the same purpose, namely, that of holding the separated cutting blades 5 and 6 in proper relationship to each other, though it is thought in practice that the provision of the shoulders 8 will be amply sufficient for such purpose.

In Figs. 1 and 2, it will be observed that I have provided an efficient cutting tool of the character specified having substantially four cutting blades, that is to say, each of the pair of cutting blades is provided with a cutting edge and any preferred edge may be readily brought into its operative position, as hereinbefore explained.

Believing that the advantages and construction and manner of using my invention have thus been made clearly apparent, further description is deemed unnecessary.

What I claim and desire to secure is:—

1. A can opener formed of a single piece of sheet metal and having a handle section and a pair of integral cutting blades, and

means integral with said handle to lie in opposed relation to each other adapted to be bent between the blades for holding the same in spaced relation with each other.

2. A cutting tool comprising a handle portion formed of a single piece of sheet metal bent upon itself substantially along its medial line, a pair of cutting blades formed upon one end of the handle portion, and integral extensions on the handle, said extensions bent between the blades for holding the same in spaced relation with each other.

3. The herein described cutting tool comprising a handle portion formed of sheet metal bent upon itself substantially along its median line, and a pair of cutting members formed upon one end of the handle portion and held parallel with each other by an integral extension from the handle.

In testimony whereof I have signed my name to this specification in the presence of two subscribing witnesses.

HENRY G. WERNIMONT.
